Attorney.

UNITED STATES PATENT OFFICE

2,404,222

DIFFRACTION GRATING TOOL

Ralph D. Doner, Auburn, Ala.

Application May 23, 1944, Serial No. 536,941

5 Claims. (Cl. 33—18)

1

My invention relates to the art of producing diffraction gratings and it particularly has for an object to provide a tool for the rapid production of an iridescent effect on commercial articles or on stock that can then be punched out and cemented onto such articles.

Other objects will in part be obvious and in part be pointed out hereinafter.

To the attainment of the aforesaid objects and ends the invention also resides in those novel details of construction, combination and arrangement of parts, all of which will be first fully described hereinafter and then be specifically pointed out in the appended claims, reference being had to the accompanying drawing in which:

Fig. 1 is an end view of the chisel member of the tool.

Fig. 2 is a side elevation of the same.

Fig. 3 is an elevation taken ninety degrees from the view in Fig. 2.

Fig. 4 is a side elevation showing the chisel member mounted on an arm or holder to form the diffraction grating tool.

Fig. 5 is a diagrammatic view explaining the action of the tool and the type of cut it is intended to produce.

Fig. 6 is an enlarged detail elevation of the chisel at the completion of one of the cuts.

In the drawing, E represents a socketed body having a threaded stem e. In the socket of the body is placed a diamond (preferably) cutter, which is held in place by suitable cement E'. Two plane surfaces A and B are ground and lapped to form an accurate edge L, with the dihedral angle approximately 90° to 115°. Two other faces C and D may be formed to clear or define the ends of the edge L.

The chisel is mounted, as shown in Fig. 4, on a bracket F that is in turn mounted at H on the arm G. The arm G is pivoted at P on a suitable support p, indicated in dotted lines in Fig. 4.

The bracket F is mounted so as to be adjustable about the axis of the portion H and clamped in any desired adjusted position, or it can be left free to turn into a position such that the edge L makes a uniform contact with the surface being worked.

The pivot P permits movement of the arm G in a vertical direction only, and it may be a short shaft with cone bearings on each end or even split-sleeve bearings allowing clamping in position as may be found desirable.

V indicates a vibrating mechanism, hereinafter again referred to.

2

The conventional technique for producing a diffraction grating requires at least two steps: 1—the preparation of the surface by grinding and polishing to mirror-like smoothness; 2—the ruling with a diamond point of individual grooves or furrows to form the non-reflecting or scattering strips, and leaving equally spaced reflecting strips in between these.

A few modifications of this process have been used, such as: ruling specially shaped grooves that reflect instead of scatter light; reproduction of master gratings by molding or stamping; and using tools with many ruling points, such as are disclosed in my Patent No. 2,102,521, and the like.

The tool of my present invention and its operation differ from the conventional in several new and radical features:

1. Instead of a point or many points, it involves a cutting edge or chisel, preferably a diamond chisel.

2. Instead of ruling furrows longitudinally, it forms the corrugations by a single transverse or crosswise stroke.

25 3. Instead of the furrows being the non-reflecting areas, the surface is machined completely into staggered or echeloned reflecting areas with no scattering areas intervening.

4. The surface need not be particularly smooth, 30 since the tool cuts away all of the old surface to a finite depth in forming the "shingle-like" echelon planes.

5. The tool may be used on a preparatory cut to machine one smooth continuous mirror-like plane; then retrace its path to form the echelon planes.

35 6. The path of one stroke of the tool is the full width of the cutting edge, say $\frac{1}{4}$ or $\frac{1}{8}$ inch, instead of say 0.0001 inch, and can cut say 2500 or more microscopic echelon planes per second; hence the speed is stepped up many hundred-fold.

40 The action of this tool requires a pulsating downward pressure against the material being ruled. This may be produced by combining a constant pressure sufficient to cause the tool to cut to the desired depth and a vibratory or alternating pressure of sufficient intensity and of such frequency as to cause the effect described below. In Fig. 4 the part shown at V is the vibrating mechanism. It may be an electromagnet actuated by A. C. or interrupted D. C., an air-driven reed, or any conventional mechanism. In fact, the vibratory pressure may be applied, 45 instead, to the surface directly, just so the re-

sulting contact pressure between the tool and the work is pulsating, and such that these two components are separately adjustable.

Fig. 5 explains the action of the tool, and the type of cut it is intended to produce. The tool is lowered (pivoting at P) onto the surface in such a position that edge L (Fig. 4) makes tangential contact. The angle between face B and the surface is adjusted as desired, preferably in the neighborhood of 10° to 20° . This causes face A to make an angle of say 50° to 80° with the surface on the other side, or as shown, to the right. Now, if the tool is given a uniform motion toward the right or, preferably, the surface is moved to the left, and only a constant contact pressure is maintained, a smooth cut will result. Adding the vibratory pressure, however, will modify the form of cut as follows: say the pulsating pressure has reached stage R, Fig. 5, and the depth of cut corresponding to it is at R'. Up to this point face A has been bearing the support of the pressure. Now as the pressure increases to phase S, the tool must sink deeper into the surface in order to give A a broader bearing area. But it cannot sink faster than the inclination of face B will allow, since B presents a uniformly increasing bearing area as the motion proceeds. Hence the cut will take the path R' to S', where S' is determined by the pressure having diminished to a point where face A can again fully support the pressure. As the pressure further diminishes from stages S to T, the tool will rise (probably on a sheer plane) to T'. Thus is achieved relatively long, but gently sloped planes R'S', T'U', etc., alternating with short but steep rises Q'R', S'T', etc.

A typical set of adjustments is to make about 10,000 of these echeloned planes per linear inch, tilted say 10° with the horizontal, and the abrupt rises at least 45° . This puts the echeloned planes out of co-planar position by a very few wavelengths of light—necessary for producing good diffraction of incident light. As high as 90% of the surface can be made optically active, instead of the conventional 50%. Furthermore, more of the light energy is concentrated in one order of spectrum, especially when the incident light is nearly normal to the echeloned planes.

This tool lends itself readily to compounding of iridescent effects, for the pitch of the vibration may be altered while the tool is active, or the rate of motion may be varied, thus producing different spacings—and consequently different optical properties are given to the surface at will. Any material that cuts smoothly may be operated upon; metals are the preferred material but fair results are obtainable on some plastics. Only parts of the surface as a rule are processed, each cut being a band the width of the chisel edge.

From the foregoing description, taken in connection with the accompanying drawing, it is thought that the construction, and operation of my new and improved tool will be clear to those skilled in the art.

What I claim is:

1. In a tool of the character described: a horizontally pivoted arm; a chisel member mounted on said arm to engage the work; and means to apply a pulsating downward pressure of the chisel against the material being cut.

2. In a tool of the character described: an arm pivotally mounted for movement in a vertical direction; a bracket carried by said arm; a chisel member carried by said bracket, said chisel member having two plane faces disposed at an angle to one another to define a straight cutting edge extending transversely to the length of said arm; and means for imparting a pulsating downward pressure on said arm and tool for purposes described.

3. In a tool of the character described: a chisel member comprising a holder, a diamond mounted in the holder, said diamond and holder having two plane surfaces meeting in a straight edge and forming an angle of 90° to 115° , said diamond having two other plane surfaces at 90° from the first two plane surfaces to define between them a predetermined length of said straight edge; a pivoted arm movable only in a direction normal to the plane of the surface to be worked on; a bracket mounted on said arm; means to mount said chisel member on said bracket with its axis inclined so as to locate one of the first two mentioned plane surfaces to make an angle of from 10° to 20° with the face of the material being worked on; and means to impart a pulsating pressure of the chisel member against and in a direction toward said material.

4. In a tool of the character described: a chisel member comprising a holder, a diamond mounted in the holder, said diamond and holder having two plane surfaces meeting in a straight edge and forming an angle of 90° to 115° , said diamond having two other plane surfaces at 90° from the first two plane surfaces to define between them a predetermined length of said straight edge; a pivoted arm movable only in a direction normal to the plane of the surface to be worked on; a bracket mounted on said arm; means to mount said chisel member on said bracket with its axis inclined so as to locate one of the first two mentioned plane surfaces to make an angle of from 10° to 20° with the face of the material being worked on; and means to impart a pulsating pressure of the chisel member against and in a direction toward said material, said last named means including a vibrating mechanism.

5. In a tool of the character described, a chisel member comprising a holder, a diamond mounted in the holder, said diamond and holder having two plane surfaces meeting in a straight edge and forming an angle of 90° to 115° , said diamond having two other plane surfaces at 90° from the first two plane surfaces to define between them a predetermined length of said straight edge; a pivoted arm movable only in a direction normal to the plane of the surface to be worked on; a bracket mounted on said arm; means to mount said chisel member on said bracket with its axis inclined so as to locate one of the first two mentioned plane surfaces to make an angle of from 10° to 20° with the face of the material being worked on; and means to impart a pulsating pressure of the chisel member against and in a direction toward said material; said last named means including a vibrating mechanism mounted on said arm.

RALPH D. DONER.
